INVENTOR.
MASA UNO.
BY Chas. E. Townsend.

ATTORNEY-

UNITED STATES PATENT OFFICE.

MASA UNO, OF SAN FRANCISCO, CALIFORNIA.

TIE PULLER.

Application filed November 3, 1920. Serial No. 421,464.

To all whom it may concern:

Be it known that MASA UNO, a subject of the Emperor of Japan, residing at city and county of San Francisco and State of California, has invented new and useful Improvements in Tie Pullers, of which the following is a specification.

This invention relates to a tie puller, more particularly to a device for pulling railroad ties from beneath rails during construction or repair of a railroad.

The object of the invention is to provide such device for pulling ties which is simple in construction and may be easily manipulated.

It is also an object of the invention that the device be so constructed that it may remain in operative position during the passage of trains and thus expedite the work of pulling ties as much as possible.

Other objects will hereinafter appear.

In carrying out the invention, a frame is provided in which there is journaled a power shaft carrying a pair of winding drums. The shaft is preferably rotated through manually operative means, and to each drum there is attached one end of a cable. The frame is positioned on one side of a railroad track, and the cables connected at their free end about the opposite end of the railroad tie to be drawn. By rotation of the drum through the means of the shaft, the tie may be withdrawn. The rotation of the shaft is accomplished by manually actuated means, and adapted to automatically decrease the turning movement of the shaft and increase its power with the increase in load upon the cables being wound about the drum. Also as the load decreases upon the cables, a reverse action will take place.

The invention is illustrated by way of example in the accompanying drawings, in which—

Figure 1 is a top plan view showing the application of my invention.

Fig. 2 is an enlarged plan view of the frame and the mechanism carried thereby, a friction disk drive for the power shaft to obtain variable speeds thereof being shown.

Fig. 3 is a plan view similar to Fig. 2, but showing gear means for replacing the friction disks shown in Figures 1 and 2.

Fig. 4 is a transverse vertical section view on line 4—4 of Fig. 3.

Fig. 5 is a transverse section on the line 5—5 of the lock plate shown in Fig. 3.

Fig. 6 is a transverse section on the line 6—6 of the lock plate shown in Fig. 3.

Referring to the drawings in detail, and particularly to Figures 1 and 2, 10 indicates a pair of rails which are laid upon ties 11 to form a road bed. In carrying out the invention, the frame 11' is provided, being substantially square in cross section with the exception of an extended portion 12 on one side thereof. The frame is substantially of the depth as shown in Fig. 4, and on each side there is secured adjacent to one end of the frame, a horizontally extended arm 13, which are adapted to seat upon the ties 11 as shown in Fig. 1. At the other end of the frame there is provided a pair of legs 14 which are adjustably secured to the frame as shown in Fig. 4. This is for the purpose that the frame may be held in any desired plane, preferably horizontally as shown.

Near the forward end of the frame there is journaled a shaft 15, extending transversely thereof. The shaft is journaled through the means of the outwardly extending bearing 16, one being formed on each side of the frame. Near the other end of the frame, a pair of outwardly extending bearings 17 are formed to journal the shaft 18. Winding drums 19 are carried by the shaft 18, and one being positioned adjacent each end thereof. To each winding drum there is secured a cable 21, which cable passes from the winding drum over a sheave 22. Each is disposed in a horizontal plane as shown, and adapted to guide the cables for winding on the winding drums 19. Each sheave 22 is rigidly supported and journaled by rigid arms 23, extending from the sides of frame 11' as shown. From the sheave 22, the cables each extend about a sheave 25, and then about a sheave 26. From this last named point the cables extend the length of a tie 11, and are connected at their ends across the end of the tie by means of a chain and hook carried on each end of the cables, as indicated at 27, Fig. 1.

The sheaves 25 and 26 are preferably disposed in a horizontal plane similar to sheaves 22. The sheaves 26 are mounted similar to the sheaves 22, that is, by means of arms 27' extending from the frame 11'. Sheaves 25 are supported by the shaft 15,

and journalled by means of pins or the like, so that said sheaves will move with the shaft. An idler 28 for each sheave may also be employed for holding the cables on the sheaves, 5 if so desired.

The shaft 15 further carries a compression coil spring 29 at its one end, said spring being secured to the shaft at its one end by means of a collar 30. The tendency of the 10 spring is to retain the shaft in the position shown at Figures 1, 2 and 3, the shaft having on its opposite end a collar 31, to limit the longitudinal movement thereof under the influence of the spring.

15 On the shaft 18 there is mounted a disk 32, having a relatively wide periphery, as shown. The disk is secured to rotate with the shaft, but adapted to move longitudinally thereof to a predetermined extent. The mounting 20 means for permitting this movement of the disk with respect to the shaft consists of a key and slot arrangement as shown. The disk 32 is formed with an extended hub 33, on one side thereof, said hub having an annular slot 25 34 adapted to accommodate the fork end 35 of the control finger 36. The control finger 36 is otherwise connected by its other end to the shaft 15, and adapted to move with said shaft.

30 The shaft 18, as before stated, is preferably manually rotated. In accomplishing this, an outwardly extending bearing 37 is formed on the adjacent end of the frame 11', and in this bearing there is journalled 35 a stub shaft 38. A disk 39 is formed on the inner end of the stub shaft, and its side surface disposed in juxtaposition to the peripheral surface of the disk 32. A spring 40 is interposed between disk 39 and frame 11' to give the required friction between the 40 driving and driven disks, namely 39 and 32, respectively. On the outer end of the stub shaft 38, there is mounted a bar and ratchet arrangement connected at 41, whereby the 45 stub shaft may be manually rotated in one direction and held against rotation in the opposite direction.

In the operation of the device as now described and shown, the frame is positioned 50 with the arms 13 on pair of ties 11, and the legs 14 are adjusted so that the frame is disposed in horizontal plane. The cables 21 are then unwound from the drums 19, and their outer ends are connected across the further 55 end of the tie 11, to be withdrawn as shown in Fig. 1. Now by applying manual power to rotate the disk 39, the disk 32 is frictionally engaged and likewise rotated. Rotation of the disk 32 will begin the winding of the 60 cables 21 upon their winding drums. When the slack has been taken up in the cables and the tie exerts a pressure against further movement, the shaft 15 will move longitudinally against the tension of the spring 29, 65 carrying therewith the sheaves 25, which

will tend to lengthen the cables 21, the same being taken up by the winding drums 19. In this longitudinal movement of the shaft 15, the control finger 36 likewise moves and carries with it the disk 32. This movement 70 is very gradual and takes place while power is continuously being applied for rotating the disks 39 and 32; as is obvious, the disk 32 moves longitudinally upon the shaft 18 toward the center of the disk 39.

75 The driving force of the disk 39 will be increased, and the turning movement of the disk 32 and likewise the shaft 18 will be correspondingly decreased. In other words, as the load increases, the driving power 80 shaft 18 will correspondingly increase to take up the excessive load. In this manner, the tie 11 will be easily withdrawn passing out beneath the frame 11'. The driving mechanism is adapted to apply a great force 85 upon the cables for withdrawing the tie.

Now referring to Figures 3 and 4, it will be seen that the disk transmission arrangement shown in Figure 2 has been substituted by gears. In this modification the 90 shaft 18 is utilized and the additional shaft 42 is also provided. This shaft is journalled in bearings 43 and 44, bearing 43 being formed on an arm 45, extending from the frame 11', and bearing 44 being formed in 95 the frame as shown. The shaft 18 carries three different gears, namely 46, 47 and 48, and likewise the shaft 42 carries the same number of gears, but are arranged in reverse relation to arrangement of the gears on 100 shaft 18. The shaft 42 is also provided on its outer end with a bar and ratchet arrangement for rotating said shaft, similar to that shown in Figures 1 and 2. The three gears mounted on the shaft 18 have their hubs 105 formed integrally, and between the first two gears there is formed a central annular groove indicated at 49. This groove is adapted to accommodate the controlling finger 36. The gears are adapted to freely slide upon the shaft 18, and as is obvious when the small gear 48 on the shaft 18 is

110 brought into mesh with the largest gear on the shaft 42, the highest turning movement of the shaft is obtained. This turning movement will be decreased and the power of the shaft increased if the gear 47 on said shaft is shifted into mesh with the next gear in size on the shaft 42. Likewise the same result would be obtained by shifting the gear 115 46 on the shaft 18 into mesh with the smallest gear carried by the shaft 42. The shifting of these gears takes place while the load increases upon the cables 21, that is, at the time of withdrawing the tie from beneath the rails. The controlling finger 36 shifts the gears similarly to the shifting of the disk 32, as previously described.

120 In order to insure that the gears will freely mesh when there is a shifting thereof, 130

I provide a lock plate 50. This lock plate is secured on its one end to an extension frame 51 formed on the main frame 11', and adapted to freely swing upwardly and downwardly. The plate has a curved portion 52 formed on its other end which is provided on its under side with the grooves 53, said grooves being three in number and each adapted to engage with either of the gears 10 carried by the shaft 18 in the manner shown in Fig. 4. Also secured on the shaft 15 is an arm 53 which has an up-turned fork portion 54 which journals and carries a roller 55. This roller operates in a groove 56 formed in the under surface of the lock plate 50. The groove is provided with rises as indicated at 57, and the arm 36 is rigidly secured to the shaft 15. As is obvious, when the shaft 15 moves longitudinally against the tension of the spring 29, this roller will engage the different rises in the groove and lift the lock plate so that it is disengaged from the gear which it may be holding. The control finger 36 in this instance is flexible 20 so that when the shaft 15 moves the finger will yield or bend and exert pressure to move the gears on shaft 18. Immediately when the lock plate is raised the gear will be shifted, and establish a new drive for the shaft 18. As before stated, three different drives may be had in this manner for the shaft 18, and the turning movement of said shaft decreased and its power increased with the increase of load upon the cables 21.

35 While I have shown the preferred form of my invention, it will be understood that various changes in the combination, construction and arrangement of parts may be made by those skilled in the art, without departing from the spirit of the invention as claimed.

Having thus described my invention, what I claim and desire to secure by Letters Patent is—

45 1. A railroad tie puller comprising, in combination, a frame adapted to be positioned at one side of a railroad track, winding means carried by said frame, cables extending from said winding means and adapted to be secured to a tie, variable speed mechanism for operating the winding means, a shiftable member for controlling the variable speed mechanism, and connections between the cables and shiftable member operative under increased tension of the cables to actuate the shifting means whereby to reduce the speed of the operating mechanism.

60 2. A railroad tie puller, comprising in combination a frame adapted to be positioned at one side of a railroad track, a shaft journalled therein carrying a pair of winding drums, a cable secured to each drum and said cables adapted to have their free ends secured about the opposite end of the

tie, means for manually rotating said winding drums and yieldable means for taking up slack in the cables during a light load thereon.

3. A railroad tie puller comprising in combination a frame, a shaft journalled therein carrying a pair of winding drums, a cable secured to each drum, means on the free ends of said cables by which they may be secured to a railroad tie, means for manually rotating said winding drums, means for taking up slack in the cables before pulling thereon by rotation of the drums, said means being yieldable.

4. A railroad tie puller comprising in combination a frame adapted to be positioned at one side of a railroad track, a shaft journalled therein carrying a pair of winding drums, a cable secured to each drum and having their free end secured by the opposite end of a railroad tie, means for manually rotating said winding drums, including a variable speed mechanism, means for taking up slack in the cables before pulling thereon is applied, said means being yieldable, and means connected between said variable speed mechanism and yieldable means whereby the turning movement of the shaft will be decreased and its power increased simultaneously with the increase of loads upon the cables.

5. A railroad tie puller comprising in combination a frame adapted to be positioned on one side of a railroad track, a shaft journalled therein carrying a pair of winding drums, a cable extending from each drum and having their ends connected by the opposite end of a tie, a pair of aligned guide sheaves between each drum and the other end of the cable, extending therefrom, a guide rod extending between said pairs of sheaves, a pair of sheaves carried by said guide rod one for each cable, and spring means for holding these last named sheaves out of alignment with a pair of aligned guide sheaves for each cable, said spring controlling sheaves being adapted to move into alignment when a load is taken up by the cables, means for rotating said drum winding shaft, including a variable speed mechanism, and connected means between the spring control sheaves and variable speed mechanism whereby the speed of the shaft will be decreased with the increased load upon the cables.

6. A railroad tie puller comprising in combination a frame adapted to be positioned at one side of the railroad track, a shaft journalled therein carrying a pair of winding drums, a cable extending from each drum and having their free ends connected by the opposite end of a tie, a pair of alignment guide sheaves carried by the frame and positioned forward to the winding drums, a guide rod extending between each of said

pairs and journalled to move longitudinally in the sides of a frame, a pair of sheaves carried by said guide rod, one for each cable, a compression spring on said guide rod 5 adapted to normally hold the last named sheaves out of alignment with the aligned pairs of sheaves, and being further adapted to be brought into alignment with the said pairs of sheaves against the tension of the

spring when a load is applied to the cables, 10 means for rotating said drum winding shaft, including the variable speed mechanism, and connecting means between the guide rod and the variable speed control mechanism, whereby the speed of the drum winding shaft will 15 be decreased with increase of load and its power correspondingly increased.

MASA UNO.
